US00D665221S

(12) **United States Design Patent**
Tosdale et al.

(10) **Patent No.:** **US D665,221 S**
(45) **Date of Patent:** **** Aug. 14, 2012**

(54) **FOOD PAN**

(75) Inventors: **David R. Tosdale**, Manitowoc, WI (US);
Theresa M. Mayer, Sheboygan, WI (US)

(73) Assignee: **The Vollrath Company, L.L.C.**,
Sheboygan, WI (US)

(**) Term: **14 Years**

(21) Appl. No.: **29/366,399**

(22) Filed: **Jul. 23, 2010**

Related U.S. Application Data

(60) Division of application No. 29/345,670, filed on Oct. 20, 2009, now Pat. No. Des. 620,306, which is a continuation-in-part of application No. 29/340,791, filed on Jul. 24, 2009, now Pat. No. Des. 613,108, which is a division of application No. 29/324,933, filed on Sep. 23, 2008, now Pat. No. Des. 597,371.

CLAIM

We claim the ornamental design for a food pan, as shown and described.

DESCRIPTION

FIG. 1 is a front perspective view from above of the claimed design;

FIG. 2 is a front view of the claimed design;

FIG. 3 is a right side view of the claimed design;

FIG. 4 is a rear view of the claimed design;

FIG. 5 is a left side view of the claimed design;

FIG. 6 is a top view of the claimed design; and,

FIG. 7 is a bottom view of the claimed design.

Any broken lines in the drawings are for illustrative purposes only and form no part of the claimed design.
